UNITED STATES PATENT OFFICE.

BERT L. GIFFORD, OF BARKER, NEW YORK, ASSIGNOR TO GIFFORD MANUFACTURING COMPANY, INCORPORATED, OF BARKER, NEW YORK, A CORPORATION OF NEW YORK.

SPRINKLING OR SPRAYING DEVICE.

1,255,405.

Specification of Letters Patent.

Patented Feb. 5, 1918.

Original application filed July 28, 1913, Serial No. 781,534. Divided and this application filed June 3, 1915.
Serial No. 31,855.

To all whom it may concern:

Be it known that I, BERT L. GIFFORD, a citizen of the United States, residing at Barker, in the county of Niagara and State 5 of New York, have invented certain new and useful Improvements in Sprinkling or Spraying Devices, of which the following is a specification.

My invention relates to sprinkling or 10 spraying devices and more particularly to what is ordinarily termed the twirler member of a sprinkling or spraying device, and it is a division of my application for patent on spraying nozzle, filed July 28, 1913, Serial 15 No. 781,534.

The primary object of my invention is the provision of a device of this type equipped with a twirler member constructed to create a fog or mist, to eject a fine spray, 20 or a drop spray resembling rain.

A still further object is the provision of a twirler which will not become clogged in spraying insecticide liquid and by means of which the spray will be spread over a 25 considerable area or be directed in a substantially straight line so as to confine the spray to a comparatively small area.

With these and other objects in view, my invention consists in the novel features 30 of construction and in the arrangement and combination of parts to be hereinafter described and more particularly pointed out in the subjoined claims.

In the drawings,—

35 Figure 1 is a side elevation of a sprinkling or spraying nozzle embodying my invention.

Figs. 2 and 3 are longitudinal sections 40 through the sprinkling or spraying nozzle taken on planes at right angles to each other, with the twirler positioned within the nozzle so as to eject a fog or mist, or a fine spray.

Figs. 4 and 5 are similar sections with the twirler reversed within the sprinkling or spraying nozzle, in which position said twirler creates a drop spray, resembling rain.

Fig. 6 is a cross section taken on line 45 6—6, Fig. 3, looking in the direction of the arrow crossing said line.

Fig. 7 is a cross section taken on line 7—7, Fig. 5, looking in the direction of the arrow crossing said line.

Figs. 8 and 9 are detached perspective views of the twirler viewed from opposite 55 sides.

Fig. 10 is a face view of the twirler showing the same in slightly modified form.

Fig. 11 is a diametrical section taken on line 11—11, Fig. 10. 60

Figs. 12 and 13 are diametrical sections through twirlers of still further modified constructions.

Referring now to the drawings in detail like numerals of reference refer to like 65 parts in the several figures.

The reference numeral 15 designates the sprinkling or spraying head or nozzle having attached thereto the liquid supply pipe 16. This head or nozzle is in the form 70 of a hollow casing or body portion provided with an internal shoulder 17 near its outer end.

Situated within said sprinkling or spraying head or nozzle is a disk-shaped twirler 75 18 which bears against the internal shoulder 17 and has its outer face flush with the outer edge of said head or nozzle. Lying against said outer edge and also against the marginal portion of the twirler is a gasket 19 against which lies a disk 20 having an escape opening 21 arranged centrally therein, the gasket 19 serving as a packing to prevent escape of the sprinkling or spraying liquid and also as a spacing member to 85 separate the disk 20 from the twirler by an intervening chamber 22. In order to retain the gasket and disk in proper place, as well as the twirler, an internally-threaded annulus 23 is provided which engages the externally-threaded outer end of said sprinkling or spraying head or nozzle. Other disks having larger or smaller escape openings may be substituted in place of the disk shown, the size of the escape opening 90 determining to a certain extent whether a fog or mist, a fine spray, or a drop spray resembling rain will be ejected.

The twirler comprises a flat substantially circular member having cut-away portions 100 24 at diametrically opposite points, and two convolute passages 25, one of the ends of these passages opening at the cut-away portions in the same transverse plane of at least part of said cut-away portions and 105 the other end of each passage terminating

and overlapping the first-mentioned end of the other passage, thereby providing passages around a central raised portion 26. Said passages are directed gradually toward 5 the axis of the twirler and are formed in one side or face of the twirler. It is to be noted that these passages are narrowest at their entrance ends, so that they are substantially self-cleansing.

- 10 At points between the cut-away portions 24 each twirler is provided on the opposite face with spacing flanges 27. The portions 24 cut away from the twirler are slightly greater than the face of the shoulder 17 formed in the sprinkling or spraying head or nozzle, which permits the liquid under pressure to pass into the two diametrically opposite spaces 28 formed by the cut-away portions 24 of the twirler and the surrounding wall of the head or nozzle. From these 20 spaces the liquid enters the convolute passages 25, where it is given a whirling motion. It thence enters into the space or chamber 22 between the twirler and the disk 25 20 where it is broken up into a fine spray or mist and finally escapes out through the escape opening 21 in said disk. To a certain extent the size of the escape opening in the disk controls the fineness of spray.
- 30 Where a straight stream is desired the twirler is reversed so that the liquid in passing through the diametrically opposite spaces 28, shown in Figs. 6 and 7, enters the space or chamber 22 without whirling action, 35 and consequently escapes through the escape opening of the disk in a comparatively straight line.

Where it is desired to deluge an extended surface or area with a spray of large drops 40 similar to rain, the twirler is provided with a number of openings 29 which, as shown in Figs. 10 and 11, are arranged in a circular course at the bottoms of the convolute passages 25 and which openings may be of different sizes. This permits the liquid to enter the space or chamber 22 of the casing 45 in larger quantities, the liquid thus entered being carried in a spiral course with the liquid entering the convolute passages 50 through the diametrically opposite spaces 28. When this twirler is used, a disk having a larger escape opening is substituted for the disk 20. A twirler of this type can be quickly substituted for the twirler first 55 described.

If it is desired to use a twirler to deluge an extended area or surface in a manner similar to rain and at times use the same for spraying, a twirler such as shown in 60 Fig. 12 may be used. This twirler has the openings 29 therein, but a regulating plate 30 is provided on the inner side of the twirler with similar openings 31, it being centrally and rotatably mounted on the 65 twirler so that in turning the same the open-

ings 29 in the twirler may be opened to the extent desired, or entirely closed.

In Fig. 13 I have shown the inner walls of the convolute grooves 25 beveled, this being brought about by tapering the central 70 portion 26 of the twirler. In spraying liquid insecticide, sediment and particles of foreign matter in the liquid often clog the nozzle, and by thus flaring the inner walls of the convolute passages, the tendency of 75 the outrushing liquid is to free the grooves of all lodging matter, the latter being carried outward onto the central portion 26 of the twirler so as to leave the convolute 80 passages free.

Having thus described my invention, what I claim is,—

1. A nozzle comprising a casing having an internal shoulder, a twirler seated against said shoulder and having a marginal cut-away portion and a convolute passage in one face of said twirler having one end thereof opening into said cutaway portion, and a disk secured to said casing spaced from said twirler, said disk having a central exit opening.

2. In a sprinkling or spraying device, a twirler comprising a circular body having marginal cutaway portions at diametrically opposite points and having in one face thereof convolute passages, the passages being spaced throughout their extent from the center of the body and each of said passages opening into one of said cutaway portions and overlapping the other passage.

3. In a sprinkling or spraying device, a twirler comprising a circular body-portion having a flat unbroken surface and flanges extending from said surface at diametrically opposite points, said body-portion being cut-away at its edge between adjacent ends of said flanges.

4. In a sprinkling or spraying device, a twirler having a circular body portion provided at diametrically opposite points with marginal cutaway portions, flanges extending from one face of said circular body portion between said cutaway portions and convolute passages in the other face of said body portion, each convolute passage opening into one of said cutaway portions and overlapping the other convolute passage.

5. A sprinkling or spraying device comprising a casing having an internal shoulder, a twirler seated against said shoulder and having marginal cutaway portions at diametrically opposite points, passages in the outer face of said twirler opening into said marginal cutaway portions, said passages being spaced throughout their extent from the center of the body, a washer seated against the end of said exit tube and closing the marginal cutaway portions of said twirler, a disk seated against said washer and having a central escape opening, and

an annulus threaded on the said exit tube and bearing against the marginal portion of said disk.

6. In a sprinkling or spraying device, a 5 twirler having a circular body portion, marginal cutaway portions at diametrically opposite points, convolute passages in one face of said body portion opening at one of their ends into said marginal cutaway portions, 10 and openings through said body portion extending from the passages to the opposite face thereof.

7. In a sprinkling or spraying device, a 15 twirler having a circular body portion, marginal cutaway portions at diametrically opposite points, convolute passages in one face of said body portion opening at one of their ends into said marginal cutaway portions, 20 openings through said body portion extending from the passages to the opposite face thereof, and means for opening or closing said openings.

8. In a sprinkling or spraying device, a 25 disk-shaped twirler having opposite marginal cutaway portions, convolute passages in one face of said twirler spaced throughout

their extent from the center of the twirler, the inner walls of said passages being tapered to render them non-clogging.

9. In a sprinkling or spraying device, a 30 twirler having a circular body portion provided with marginal cut-away portions at diametrically opposite points extending from face to face thereof, convolute passages in one face of said body portion opening at 35 one of their ends into said marginal portions, and flanges at diametrically opposite points projecting from the opposite face of said twirler and extending from cut-away portion to cut-away portion of said body 40 portion.

10. In a sprinkling or spraying device, a 45 twirler comprising a circular body portion having a flat unbroken surface, and flanges extending from said surface at diametrically opposite points, said body portion being cut-away at its edge between adjacent ends of 50 said flanges and the edge of said body portion where cutaway between said flanges being eccentric.

In testimony whereof I affix my signature.
BERT L. GIFFORD.
